(57) **CLAIM**

The ornamental design for a light emitting sheet with surface pattern, as shown and described.

DESCRIPTION

A portion of the material in this patent document is subject to copyright protection under the copyright laws of the United States and of other countries. The owner of the copyright rights has no objection to the facsimile reproduction by anyone of the patent document or the patent disclosure, as it appears in the United States Patent and Trademark Office publicly available file or records, but otherwise reserves all copyright rights whatsoever. The copyright owner does not hereby waive any of its rights to have this patent document maintained in secrecy, including without limitation its rights pursuant to 37 C.F.R. § 1.14.

FIG. 1 is a plan view of a light emitting sheet with surface pattern showing a first embodiment of my new design in an illuminated state.

FIG. 2 is a plan view thereof, in a non-illuminated state. FIG. 3 is a plan view of a light emitting sheet with surface pattern showing a second embodiment of my new design in an illuminated state; and,

FIG. 4 is a plan view thereof, in a non-illuminated state. The broken lines represent the bounds of the claim and form no part of the claimed design.
